UNITED STATES PATENT OFFICE.

HARRY A. DAVIS, OF HOPEDALE, MASSACHUSETTS, ASSIGNOR TO DRAPER CORPORATION, OF HOPEDALE, MASSACHUSETTS, A CORPORATION OF MAINE.

WARP STOP MOTION FOR LOOMS.

Application filed March 9, 1923. Serial No. 624,015.

To all whom it may concern:

Be it known that I, HARRY A. DAVIS, a citizen of the United States, and a resident of Hopedale, county of Worcester, State of Massachusetts, have invented an Improvement in Warp Stop Motions for Looms, of which the following description, in connection with the accompanying drawing, is a specification, like characters on the drawing 10 representing like parts.

This invention relates to warp stop motions for looms. Such warp stop motions commonly include one or more banks of so-called drop wires. These drop wires are suspended on the warp and guided or supported in position usually by one or more drop wire supports each in the form of a thin flat vertically disposed bar extending transversely across the loom and passing through slots 20 in the drop wires. The sheet of warps is usually supported and guided adjacent the drop wires by passing over a plurality of warp rest bars extending parallel with the drop wire supports. Owing to the necessarily thin and yieldable character of the drop wire supports it is common, especially in the wider types of looms, to provide one or 25 more bridge pieces the function of which is to brace and hold in position the drop wire supports.

The main object of this invention is to provide a simple and efficient form of bridge piece which can readily be moved into and out of its operative position to enable the 35 drop wire support readily to be moved and replaced in the loom or to enable the drop wires to be shifted along and re-arranged on the drop wire support as required by the weaving operation.

The nature and object of the invention 40 will appear more fully from the accompanying description and drawings and will be particularly pointed out in the claims.

In the drawings:

Fig. 1 is a rear elevation of a portion of a 45 warp stop motion embodying a preferred form of the invention;

Fig. 2 is a view in end elevation and partially in vertical cross section of the construction shown in Fig. 1 with the drop wires indicated in dotted lines and with the unlocked or inoperative position of the bridge piece indicated in dotted lines.

As the general type of warp stop motion 50 with which this invention is concerned is

well-known and familiar to those skilled in the art it is only necessary here to illustrate and describe in detail those parts of the mechanism particularly concerned with the present invention.

The warp stop motion mechanism is usually mounted near the rear end of the loom and extends transversely from side to side of the loom. The drop wires employed are commonly thin flat metal pieces, such for example as illustrated at 1. Each drop wire is provided with a hole through which a warp passes and each is usually slotted vertically as at 2. These drop wires are mounted in one or more banks or rows depending upon the number of warp in the loom. Each bank of drop wires is usually supported and guided on a drop wire support. In the illustrations there are shown two of these banks of drop wires and consequently two drop wire supports 3 and 4. Each drop wire support consists of a thin flat bar standing vertically and extending transversely across the loom and passing through the slots 2 in the drop wires. Thus the drop wires are held in accurate alignment and definite position.

The sheet of warp 5 extending through the drop wires is usually supported upon a plurality of warp rest bars which may vary in construction as desired. In the form illustrated the two outermost warp rest bars 6 and 6 are of similar construction being formed of metal bent into a U-shape and secured in a suitable manner to the loom sides so that they extend across the loom parallel with the drop wire supports 3 and 4. The intermediate warp rest bar illustrated at 7 is in the form of a round rod, also extending across the loom. The upper surfaces of these warp rest bars 6 and 6 are in the same plane and in a suitable proximity to the banks of drop wires which are arranged alternately therewith. The drop wires are held in elevated position as shown in the drawings.

It is unnecessary to describe the operation of the warp stop motion in detail but it will be understood that when a warp breaks the corresponding drop wire being released drops or falls being guided down upon its drop wire support. The dropped wire thus comes usually into the path of a rocking feeler, not shown, carried by the shaft 8 mounted in a bracket 9 depending from the warp

rest bars 6 and 6. The engagement of the feeler with the dropped wire is utilized to stop the loom.

It will be seen that the drop wire supports 3 and 4 are necessarily thin flexible bars because they must extend through the drop wires and must be of a considerable length especially in the wider type of looms. In order to hold these drop wire supports in their proper operative position and to brace and support them the bridge piece of this invention is provided.

A bracket of suitable form is supported in rigid relation to one of the warp rest bars at 15 the rear side thereof. Such a bracket 10 is illustrated secured to the outer side of one warp rest bar 6 by the same bolts which hold the bracket 9 in place. The bracket 10 is provided with an upstanding and rearwardly projecting arm 11. The bridge piece is in the form of a thin flat piece of metal 12 which may be of any suitable shape such for example as that illustrated. At the rear end this bridge piece is provided with a 20 vertically slotted portion 13 fitting over a stud 14 in the arm 11. This stud is provided with a clamping nut 15. At the front end the bridge piece is provided with a depending projection 16 so arranged that when 25 the bridge piece is in the operative locked position shown in Fig. 1 and in full lines in Fig. 2 the bridge piece will rest on the top of the warp rest bars 6 and 6, and this projection will engage the outer face of one 30 warp rest bar 6. On the under side the bridge piece is slotted at 18 to fit over the drop wire supports 3 and 4, there being as many of these slots as there are drop wire supports.

40 The bridge piece is provided with a locking catch to engage and lock against one of the warp rest bars. In the construction illustrated this locking catch co-operates with the central warp rest bar 7 which is in the 45 form of a round rod. The locking catch is shown as comprising a shank 19 threaded at 20 and provided at its lower end with a hook 21 and at its upper end with a knurled cap 22. The shank of the locking catch passes through vertically aligned lugs in the 50 bridge piece so that the locking catch is mounted in the bridge piece both for rotary and longitudinal movement. A knob or 55 projection 23 on the shank limits the movement in either direction of the locking catch and a thumb nut 24 on the threaded portion of the shank abuts against the top of the bridge piece and enables the locking catch to be drawn up tightly in its locked position.

60 The operation of the device will be apparent. When the bridge piece is in its operative or locked position the hook 21 of the locking catch engages beneath the warp rest bar 7 and the thumb nut 24 being screwed down holds it in locking engage-

ment. When it is desired to remove the drop wire supports 3 and 4 or to shift the drop wires along the drop wire supports or re-arrange them in different position according to the requirements of the loom the operative unscrews the thumb nut 24 thus lowering the locking catch until it is out of engagement with the bar 7 and then by means of the catch 22 turns the locking catch until it extends parallel with the warp stop bar 7. 70 He then loosens the nut 15 and raises the bridge piece on the stud 14 until it is clear of the drop wire supports and then swings it rearwardly to the dotted line position shown in Fig. 2. Thus free access is had to 80 the drop wire supports.

It is obvious that there may be as many of these bridge pieces as required and that they may be located at any desired points transversely of the loom.

Having thus described the invention, what is claimed as new, and desired to be secured by Letters Patent, is:

1. A warp stop motion for looms comprising a pair of longitudinally extending parallel warp rest bars, a longitudinally extending drop wire support parallel with and intermediate of the warp rest bars, a bracket supported in rigid relation to one of the warp rest bars at the outer side thereof, a bridge piece mounted for vertical and transverse rocking movement on the bracket, extending transversely over the warp rest bars and drop wire support and slotted in its under side to engage and position the drop wire support, and a locking catch movably mounted in the bridge piece and acting when in locking position to have a locking engagement with a warp rest bar and when in unlocking position to be disengaged from the warp rest bar and permit the bridge piece to be raised off the drop wire support and swung to one side.

2. A warp stop motion for looms comprising a pair of longitudinally extending parallel warp rest bars, a longitudinally extending drop wire support parallel with and intermediate of the warp rest bars, a bracket supported in rigid relation to one of the warp rest bars at the outer side thereof, a bridge piece mounted for vertical and transverse rocking movement on the bracket, extending transversely over the warp rest bars and drop wire support and slotted in the under side to engage and position the drop wire support, a locking catch having a shank mounted in the bridge piece for rotary and vertical movement and having a hooked lower end to engage beneath a warp rest bar, and means for longitudinally and rotarily adjusting the locking catch in the bridge piece to permit locking engagement and disengagement of the hooked end with the warp rest bar.

3. A warp stop motion for looms com-

prising the construction defined in claim 2 in which the shank of the locking catch is threaded and a threaded nut abutting the bridge piece is mounted on the threaded shank to secure the longitudinal adjustment of the locking catch.

4. A warp stop motion for looms comprising a plurality of longitudinally extending parallel warp rest bars, a plurality of longitudinally extending drop wire supports arranged parallel with, alternately of, and intermediate the warp rest bars, a bracket supported in rigid relation to one of the warp rest bars at the outer side thereof, a bridge piece mounted for vertical and trans-

verse rocking movement on the bracket, extending transversely over the warp rest bars and drop wire supports and slotted in the under side to engage and position the drop wire supports, and a locking catch movably mounted in the bridge piece and acting when in locking position to have a locking engagement with one of the warp rest bars and when in unlocking position to be disengaged from the said warp rest bar and permit the bridge piece to be raised off the drop wire supports and swung to one side.

In testimony whereof, I have signed my name to this specification.

HARRY A. DAVIS.
